THOMAS H. RILEY, OF SKANEATELES FALLS, NEW YORK, AND ALSTON H. FLINT, OF WORCESTER, MASSACHUSETTS, ASSIGNEES TO JOHNSON & BASSETT, INC., OF WORCESTER, MASSACHUSETTS, A CORPORATION OF MASSACHUSETTS.

BUNCH BUILDER FOR SPINNING MULES.

Application filed June 17, 1926. Serial No. 116,732.

This invention relates to mule spinning machines.

In automatic looms the discharge of bobbins from the loom is controlled by a feeler 5 on the loom which contacts with the bobbin and causes it to be thrown out when the bobbin is nearly empty. It is necessary, however, to leave a small amount of yarn on the bobbin after the feeler has functioned, 10 in order to enable the shuttle to complete the pick. For this reason the bobbin is wound with a bunch at or adjacent the base of the bobbin to provide this required reserve supply of yarn.

15 It has been necessary in many woolen mills to rewind spun yarn for use in automatic looms because of the fact that in winding bobbins in the usual way on the mule the yarn could not be properly shaped on the 20 bobbin to be suitable for use in automatic looms. In other words, the usual faller control in a spinning mule does not provide for building a bunch on the bobbins. This re-winding of the bobbins requires the expenditure of time and labor and is a source of 25 considerable expense.

With the above problems in mind, the present invention has for its salient object to provide an attachment for a spinning mule 30 so constructed and arranged as to build a bunch on the bobbins.

Another object of the invention is to provide a bunch builder attachment for a spinning mule, so constructed and arranged that 35 the size of the bunch can be controlled, and after a bunch of the desired size has been built the attachment will be automatically rendered inoperative and the mule will operate in the usual manner.

40 A further object of the invention is to provide a bunch builder for a spinning mule so constructed and arranged that exactly the same amount of yarn will be contained in the bunch on each bobbin.

45 A still further object of the invention is to provide a builder rail control device so constructed and arranged that the rail will be supported in position to build a bunch and will thereafter return to its normal 50 operation.

Further objects of the invention will ap-

pear from the following specification, taken in connection with the drawings which form a part of this application, and in which

Fig. 1 is a front elevation of the back end 55 portion of a builder rail showing the back shoe and the bunch builder attachment;

Fig. 2 is an elevational view showing the front end portion of the builder rail and control mechanism associated therewith; 60

Fig. 3 is a top plan view of the structure shown in Fig. 1;

Fig. 4 is a top plan view of the structure shown in Fig. 2;

Fig. 5 is a longitudinal sectional view 65 taken through the bunch builder attachment, this view being taken substantially on line 5-5 of Fig. 3;

Fig. 6 is an elevational view looking in a direction opposite to Fig. 2 and showing the 70 back off lever and back off rod; and

Fig. 7 is an elevational view forming a vertical continuation of the showing in Fig. 1, and illustrating the mule carriage, the upper portion of the faller leg, the faller wires, 75 and associated parts.

The invention briefly described consists of a bunch builder attachment for spinning mules. This attachment comprises a supplemental bunch builder shoe for holding the 80 builder rail or a portion thereof in position to control the faller leg and faller wire so as to wind a bunch of yarn on the bobbins near the base thereof.

The supplemental shoe is placed in juxtaposition to or side by side with relation to the back builder shoe, and when the supplemental shoe is operating the control of the back portion of the builder rail is taken away from the back shoe and exercised by 90 the supplemental shoe. The supplemental shoe is placed in operative position by the rotation of the re-set mechanism for the builder shoes and is retained in operative position for a predetermined number of 95 draws. The shoe-control cam plate which moves the shoe to operative position and supports the supplemental shoe in operative position can be so adjusted that a bunch of the desired size can be built, and this cam plate is fed at each draw of the loom in such a way that after a predetermined number of 100

draws the plate will be lowered thereby, permitting the supplemental shoe to drop out of operative position.

Further details of the invention will appear from the following specification.

The spinning mule disclosed herein is of the usual construction, and therefore, the details of construction and the details of the operation of the various parts of the mule 10 need not be described at length.

Briefly stated, the mule comprises a builder rail which is made up of a back section 10 and a front section 11. The back section 10 has a roller 12 secured thereto, the 15 front section 11 has a roller 13 secured thereto, and a third roller 14 is disposed at the junction of the sections as shown in Fig. 2. The central portion of the shoe is guided vertically by a U-shaped bracket 15 in which 20 is positioned a stud 16 on the outer end of which the roller 14 is mounted.

The builder rail is normally supported on three builder shoes, a back shoe 20, a center shoe 21, and a front shoe 22, and these shoes 25 are slidably mounted on suitable bases and are connected to and controlled by a builder rod 25 of the usual construction. The builder-rod is fed longitudinally by means of a quadrant lever 26 which is engaged by 30 a roller 27 carried by an arm 28 secured to the carriage. It will be evident that each time the carriage moves to the front of the machine the quadrant lever 26 will be tilted on its axis 29. As in the usual construction 35 the quadrant lever feeds a pawl 30, which in turn rotates a ratchet wheel 31 carried by a shaft 32. This shaft has formed thereon a screw 33 which engages a threaded bracket 34 secured to the builder rod 25. A 40 crank handle 36 is secured to the outer end of the shaft or spindle 32 for manually resetting the shoes after the winding of the bobbins has been completed.

The builder rail performs its usual function 45 of controlling the winding of the yarn on the bobbins. The rail is engaged by a roller 40 carried by a builder arm 41 slidably mounted on the builder carriage 42, and the builder arm 41 also has a roller or stud 43 50 adapted to be engaged by a notch 44 in the faller leg 45, when the mule is in position to wind the yarn. The faller leg 45 is connected in the usual manner to the faller rod 46 on which are mounted the faller or 55 guiding fingers 47 having faller wires 48 secured thereto. These fingers control the course of the yarn being wound on the bobbins and operate in the usual well-known manner.

60 It will be understood, without further explanation, that when the builder shoes are so located as to raise the builder rail at the back end thereof, the faller leg will also be raised, lowering the faller rod and the faller 65 guiding fingers 47.

The spinning mule illustrated also has the usual back-off lever 50 which controls the back-off rod 51 and is actuated in the usual and well-known manner by a roller 52 mounted on the mule carriage to reverse the 70 drive at the desired point and cause the carriage to travel backwardly from the front of the machine.

All of the construction above described is common in the art and forms no part of 75 the present invention.

Bunch builder attachment.

The present invention as above explained, has for its object to provide means for taking 80 the control of the builder rail away from the back builder shoe 20 and for so positioning the rail as to cause the faller leg and faller wires to build a bunch adjacent the base of 85 the bobbins.

The attachment is mounted on a base-plate 60 having a pair of cam surfaces 61 and 62 extending upwardly therefrom. These surfaces are adapted to co-act with cam surfaces 63 and 64 formed on the supplemental shoe supporting member 65. The supplemental shoe 66 is slidably mounted by a pin and slot connection 67 on the back shoe 20, and rests, as shown in Fig. 5, on the upper surface 68 of the shoe-supporting 90 member 65. In Fig. 5 the supporting member is shown in operative position, or in elevated position on the cam surfaces 61 and 62, and it will be evident from the showing in this figure, that the control of the 95 back roller 12 and the back portion of the builder rail is exercised by the supplemental shoe 66 and has been taken away from the back shoe 20.

The supplemental shoe supporting mem- 100 ber 65 is moved manually to operative position as shown in Fig. 5, but is automatically returned to inoperative position after a predetermined number of draws.

The shoe is moved to operative position 105 by means of a pawl 70 which is pivoted to an adjustable bracket 71 secured to the builder rod 25. The front end of the pawl 70 is adapted to engage a pin 72 carried by the front end of the supplemental shoe sup- 110 port 65. The pawl 70, as shown in Fig. 1, has a lug 73 extending upwardly therefrom, and a pin 74 is carried by the lug and is adapted to engage an inclined lug 75 which 115 is formed on the base 60 when the plate 65 is moved to operative position as shown in Fig. 5.

120 It will be understood that the builder shoes must be reset after one set of bobbins has been wound, and as above explained, this is accomplished by manually rotating the crank handle 36 and thus moving the builder rod longitudinally in position to reset the builder shoes. As this rod is moved longitudinally it will also reset the supple- 125 130

mental builder shoe 66 since the pawl 70 will draw the supplemental builder shoe support 65 and raise the support on the cam surfaces 61 and 62.

- 5 As above stated after the predetermined number of draws, the supplemental builder shoe is put out of commission. This is accomplished by a pawl 80 pivotally mounted at 81 on a bracket 82 secured to and 10 carried by the back-off rod 51. The pawl 80 is adapted to engage rack teeth 83 of a rack 84 adjustably secured, as shown at 85, to the upper surface of the support 65. The pawl 80 has a pin 86 extending laterally 15 therefrom and engaging a cam surface 87 and the pin is adapted to ride back and fourth on this cam surface when the supplemental rail is in inoperative position as shown in Fig. 1.
- 20 When the rail is in operative position, however, as shown in Fig. 5, the pawl and cam are so relatively positioned that the pawl will feed the rack and support 65 a distance corresponding to one rack tooth 25 for each reciprocation of the back-off rod 51. The number of draws necessary to feed the support 65 to a position in which the cams 61 and 62 will enter the recesses formed by the cams 63 and 64 is determined by the 30 adjustment of the rack bar 84.

Operation.

The bunch builder attachment operates as follows:—

- 35 The crank 36 is first rotated in a direction to move the builder rod longitudinally and position the builder shoes in operative position to start the operation of the machine. Assuming that a bunch is to be built on the 40 bobbins, the movement of the builder rod will cause the pawl 70 to elevate the support 65 for the supplemental builder shoe 66 to the position shown in Fig. 5. In this position it will be seen that the control of the 45 back end of the builder rail is taken away from the builder shoe, and is exercised by the supplemental builder shoe 66. The supplemental builder shoe will remain in commission until the support 65 is fed step 50 by step by the pawl 80 by drawer, and after a predetermined number of draws the support 65 will reach a position in which the cams 61 and 62 enter the recesses formed by the cams 63 and 64, thus lowering the supplemental builder rail to inoperative position 55 as shown in Fig. 1.

From the foregoing specification it will be seen that a simple and practical attachment has been provided for spinning mules, 60 whereby a bunch having the desired number of turns or windings can be built on the bobbins.

Furthermore, it will be evident that all of the bunches on the bobbins will be uniform 65 in size and shape by reason of the bunch

builder attachment. The necessity for re-winding the bobbins which have been wound on spinning mules is obviated, thus effecting a material saving in time, labor and expense.

Although one specific embodiment of the 70 invention has been particularly shown and described, it will be evident that the invention is capable of modification, and that changes in the construction and in the arrangement of the co-operating parts may be 75 made without departing from the spirit and scope of the invention as expressed in the following claims.

What we claim is:—

1. In a spinning mule, a builder rail, a 80 plurality of shoes supporting said rail, a builder rod controlling said shoes, a supplemental shoe disposed adjacent one of said shoes, means for moving said supplemental shoe to operative position and for supporting said shoe in position to engage and support the rail, and operative connections including a rack and pawl connection between said rod and said moving and supporting means for automatically rendering said supplemental shoe inoperative after a predetermined number of draws. 85

2. In a spinning mule, a builder rail, a shoe adapted to engage and support said rail, means for moving said shoe to operative position and for holding the shoe in operative position, and automatically operable control means including a back off rod for rendering said shoe inoperative after a predetermined number of draws. 95

3. In a spinning mule, a builder rail, a shoe for engaging and supporting said rail, a supplemental shoe disposed side by side with said first shoe, means for moving said supplemental shoe into engagement with the 100 rail whereby the rail will be supported thereby, and means including a back-off rod and automatically operable after a predetermined number of draws for rendering said supplemental shoe inoperative and said first shoe 105 operative to support the rail.

4. In a spinning mule, a builder rail, a shoe for engaging and supporting said rail, a supplemental shoe disposed side by side with said first shoe, means for moving said supplemental shoe into engagement with the rail, whereby the rail will be supported thereby and means including a back-off rod and operative connections between said rod and the shoe moving means automatically 115 operable after a predetermined number of draws for rendering said supplemental shoe inoperative and said first shoe operative to support the rail.

5. In a spinning mule, a builder rail, a builder shoe engaging said rail, a supplemental shoe adjacent said builder shoe and adapted to coact with the builder rail, a builder rod connected to said first shoe and adapted to move said shoe relative to the 125 130

rail and means independent of said builder rod for moving said supplemental shoe.

6. In a spinning mule, a builder rail, a bunch builder shoe adapted to engage and support said rail, means for moving the shoe to and supporting the shoe in operative position, a back off rod, a back off lever con-

nected thereto and means controlled by said back off rod for rendering said shoe inoperative after a predetermined number of draws. 10

In testimony whereof we have hereunto affixed our signatures.

THOMAS H. RILEY.
ALSTON H. FLINT.
